RADIO RECEIVER AND RESISTANCE CORD

Carl T. Mason and Byron B. Minnium, Chicago,
Ill., assignors to Stewart-Warner Corporation,
Chicago, Ill., a corporation of Virginia

Application February 13, 1933, Serial No. 656,438

2 Claims. (Cl. 250—27)

This invention relates to a new and improved electrical conductor cord or the like, and more particularly to a multiple conductor including both high and low resistance units.

5 With various types of devices to be operated from regular commercial electric current lines, it is desirable or necessary to reduce the voltage between the line and the device being operated. Examples of such devices are radio sets and motion picture projectors. With many such devices 10 it is customary to locate the resistance within the set or under or upon the mounting of the projector. The usual types of resistances are bulky and must be provided with ventilation to dissipate 15 the heat generated during the use of the resistance. Both of these difficulties are particularly objectionable in connection with certain types of small radio sets which have been developed for use upon commercial current lines whether direct or alternating current.

We have illustrated and described our invention in relation to such a radio set but it is to be understood that it is adapted for a wide variety of other uses where a resistance is necessary or 25 desirable, such as in connection with motion picture projectors, small motors, therapeutic lamps or other devices.

It is an object of the present invention to provide a new and improved electrical conductor cord or the like including a high resistance element.

It is also an object to provide a multiple conductor including both low and high resistance conducting elements.

35 It is an additional object to provide a multiple conductor including low and high resistance units connected in parallel.

It is a further object to provide a multiple conductor of the type described in which the high 40 and low resistance elements are insulated from each other both electrically and thermally.

It is also an object to provide a multiple conductor adapted for use with different voltages of supply current and adapted for adjustment in 45 accordance with such voltage.

Other and further objects will appear as the description proceeds.

We have shown in the accompanying drawings 50 certain preferred embodiments of our invention. Figure 1 is a diagrammatic showing of a radio circuit with our improved conductor in association therewith;

Figures 2, 3, 4 and 5 are views similar to Figure 55 1, with the radio receiver merely indicated in the

figures and with modified forms of conductor shown diagrammatically;

Figure 6 is a section on an enlarged scale taken on line 6—6 of Figure 2;

Figure 7 is an enlarged section taken on line 7—7 of Figure 3;

Figure 8 is a view similar to Figure 2, but showing a modified form of conductor;

Figure 9 is a section on line 9—9 of Figure 8; and

Figure 10 is a view similar to Figure 8 but showing a further modification.

Referring first to Figure 1, the radio circuit is shown in schematic form including the radio frequency amplifying tube 11, the detector tube 12 and audio amplifying tube 13. The rectifier tube is shown at 14. The multiple conductor 15 is shown as provided with a usual type of two-prong plug 16 having prongs 17 and 18 adapted for insertion in any usual type of receptacle. The 75 prong 17 is connected to the low resistance conductor 19, which conductor is connected to the electrode 20 in the rectifier tube 14.

The low resistance conductor 21 is connected to prong 18 and in the set is connected through line 80 22 to line 23 which, through line 24, is connected to the filament or heater element 25 in the detector tube 12. This element 25 in tube 12 is connected by wire 26 to the similar element 27 in tube 11. Element 27 is connected by the 85 wire 28 to the similar element 29 in tube 13. The other side of the element 29 is connected through wire 30 to the element 31 in the rectifier tube 14. The other side of element 31 is connected by wire 32 to the high resistance conductor 33 in 90 the multiple conductor 15. This high resistance conductor 33 is connected in parallel in the conductor 15 to the low resistance conductor 19 at a point adjacent the plug 16.

It will be understood that the high resistance 95 conductor 33 may be of any desired length and extend through any part of the multiple conductor 15, depending upon the resistance of the wire used in conductor 33, the length of the multiple conductor, and the amount of resistance it is desired to insert in the line.

With four tubes of the type shown in use in radio sets at the present time, and with the filaments connected in series, the resistance in the conductor 33 should be approximately 280 ohms, 105 with a 110 volt source of current. It will be understood that the showing of Figure 1 is schematic and that the invention is adapted for use with other types of radio circuits in which tubes may be connected in series or in parallel as desired, de- 110

pending upon the tube characteristics and the voltage of the line. It will also be understood that the particular radio circuit shown may be modified and supplied with filters, chokes and other refinements.

By the use of the multiple conductor, including two low resistance conductors, the proper voltage drop may be provided between the electrodes in the rectifier tube as well as supplying the filament current for all of the tubes, which latter current is passed in series through the high resistance conductor. In Figure 1 the three conductor elements have been shown schematically as carried in parallel through the multiple conductor. 15 This form of construction may be used or the forms of construction shown in Figures 2 and 3, which merely differ as to the relation to the three conducting elements.

In Figure 2 the low resistance conductors 40 and 41 are shown twisted with the high resistance conductor 42. This multiple conductor is shown in section on an enlarged scale in Figure 6. The low resistance conductors 40 and 41 are shown as provided with insulating casings or sheaths 43 and 44. These casings or sheaths may be formed of fabric and rubber, or any other usual insulating material. The high resistance conductor 42 is shown as consisting of a spiral coil which is wrapped spirally around a core 45 and is enclosed in a sheath 46. This sheath 46 in addition to being an electrical insulator is also preferably provided with one or more layers of asbestos or other heat insulating material. The three conductors are shown as enclosed in a fabric sheath 47.

35 The form of construction shown in Figure 3 includes the low resistance conductors 51 and 52 provided with the insulating sheaths 53 and 54. These conductors 51 and 52 are carried parallel and spirally wrapped around them is a high resistance conductor 55. The conductor 55 is in turn enclosed in an asbestos sheath 56 with an outer fabric covering 57.

The forms of construction shown in Figures 4 and 5 differ from those previously described in that the high resistance conductor extends only part way through the length of the multiple conductor. In the tube shown in Figure 4, the insulating housing 61 encloses the low resistance conductors 62 and 63 and the high resistance conductor 64. These conductors are connected to usual types of wires or other flexible low resistance conductors 65, 66 and 67 respectively, these wires leading to the radio receiver. The sheath 61 may be of greater or less longitudinal extent and may be directly incorporated in a plug structure having the prongs 68 and 69 for the usual type of connector. The housing 61 may be both thermally and electrically insulated and if desired may be flexible in character.

60 In the form of construction shown in Figure 5, the plug 71 is provided with prongs 72 and 73 which connect to wires 74 and 75. The wire 75 connects in the sheath or housing 76 to the high resistance conductor 77 and the low resistance conductor 78. The wire 74 connects in the housing 76 to the low resistance conductor 79. In this case the housing or sheath is located immediately adjacent the radio receiver rather than adjacent the plug. Where the extension of such a housing adjacent the receiver is not objectionable, this construction has the advantage over that in Figure 4 in that only two conductor wires are necessary between the housing and the plug.

75 In the form of construction shown in Figure 8,

there is provided an adjustably connected plug 81 which includes the section 82 provided with prongs 83 and 84 for insertion in the usual types of receptacles. The multiple conductor is shown as containing two low resistance wires 85 and 86, a high resistance wire 87, and a resistance wire 88 of greater resistance than the wire 87. This plug 81 is shown schematically in Figure 9, and an arcuate contact 89 may be connected permanently to the prong 83, while a small circular contact 90 is permanently connected to the prong 84. The contact 91 may be permanently connected to the low resistance wire 85 so that that wire is connected to prong 83 in all of the three adjusted positions of the plug.

With the parts in the intermediate position shown in Figure 8, the contact connected to the wire 87 is aligned and in contact with the contact 90 connected to prong 84. The contact 91 would be permanently connected to the low resistance wire 86, and contact 92 connected to the higher resistance wire 88. The multiple conductor has been shown connected to a radio receiver 93. While an adjustable multiple conductor of this character is adapted for use with a variety of current-using devices, it has been shown in connection with the radio receiver and voltages of 6, 32 and 110 have been indicated on the plug section 81. For example, where the source of voltage connected through prongs 83 and 84 is a storage battery or other device delivering six volts, the two low resistance conductors 85 and 86 may be connected. If the voltage delivered is 32 volts, as for example from what are commonly called farm lighting systems, the resistance of the line 87 may be adequate taken in connection with the low resistance conductor 85 to deliver the proper voltage to the receiver. For use with a 110 volt source of current the high resistance 88 may be connected in association with the low resistance conductor 85.

The form of construction shown in Figure 10 offers a possibility of delivering a multiplicity of voltages to a radio receiver or any other device from a source of current having a single voltage. 120 The plug 101 is shown as having the prong 102 which is connected to a low resistance wire 103 and a high resistance wire 104. The prong 105 is shown connected to a low resistance wire 106, a high resistance wire 107, and a higher resistance 125 wire 108. All wires lead to the radio receiver 109. It will be apparent that cross connections may be made in the receiver in a variety of ways between the several conductors which vary in resistance. For example, a cross connection between conductor 104 and conductor 108 would give a low voltage. A connection between conductor 104 and conductor 107 would give a higher voltage. A connection between conductor 104 and 106 would give a still higher voltage, while 130 a connection between conductors 103 and 106 would deliver to the receiver or other device, substantially the full voltage of the power line. It will be apparent, therefore, that a multiple conductor of this character is adapted to deliver a 140 multiplicity of voltages and thus eliminate the necessity for numerous resistors which are commonly used in radio receivers.

While the drawings have shown several types of construction it will be understood that our invention is capable of either change or modification to meet varying conditions and requirements. Also, as has been previously stated, it may be used in connection with other devices than a radio receiver. We therefore contemplate such 150

changes and modifications as come within the spirit and scope of the appended claims.

We claim:

1. In combination with a radio receiving set having a vacuum tube as a part thereof, an electrical multiple conductor external to said radio set, said conductor comprising a high resistance conducting element and a low resistance conducting element, said conducting elements being in parallel in said conductor and both said conducting elements being connected in series with said vacuum tube, the high resistance element to the filament of said tube and the low resistance element to another electrode in said tube.

2. In combination with a radio receiving set

having a receiving vacuum tube and a rectifying vacuum tube as parts thereof, a multiple electrical conductor external to said radio set and electrically connected between said set and a high potential source of current, a pair of low resistance conducting elements and a high resistance conducting element in said conductor, the high resistance element and one low resistance element being connected in series with the filaments of the receiving and rectifying tubes, and the other low resistance element being connected in parallel with the high resistance element and to an electrode in the rectifying tube.
